UNITED STATES PATENT OFFICE.

FRANKLIN MASON DESSART, OF BROOKLYN, NEW YORK.

MASK.

1,391,617.

Specification of Letters Patent. Patented Sept. 20, 1921.

Application filed September 25, 1920. Serial No. 412,673.

To all whom it may concern:

Be it known that I, FRANKLIN M. DESSART, a citizen of the United States, and a resident of the city of New York, borough 5 of Brooklyn, county of Kings, and State of New York, have invented a new and Improved Mask, of which the following is a full, clear, and exact description.

In connection with masks, it is a well appreciated fact that it has been customary to form the same of usually three pieces. The parts provided with the eye openings, nose, etc., were commonly formed of one piece of material, to the rear face of which a second 15 piece of material, commonly cheesecloth was affixed. These two pieces of material were superimposed, and usually provided with a gummy solution on their abutting faces, subsequent to which they were passed 20 under a die, cutting the eye openings, the exterior contour of the face portion of the mask, nose bulge, together with forcing these pieces of material into intimate contact one with the other, and in some instances providing a reinforcement adjacent the side 25 edges.

Subsequent to the forming of this portion of the mask, an apron was cut by the second die, which apron was sewn adjacent 30 the lower end of the piece already formed so as to provide a curtain or covering for the lower portion of the face.

This procedure has involved considerable expense, in that manual labor was employed 35 to attach the apron. Aside from this objection, the apron was liable to be torn from the mask proper in handling the same, aside from the fact that an unsightly ridge was provided at the points of connection of 40 these two portions.

With this in view, I have constructed a mask which shall avoid these objections, in that it will not be necessary to attach the apron to the mask or body portion thus 45 eliminating the objections incident to this procedure.

Reference is had to the attached sheet of drawings as illustrating one practical embodiment of my invention, and in which—

50 Figure 1 is a front view of a mask con-

structed in accordance with my invention, and

Fig. 2 is a side view taken along the line 2—2 of Fig. 1.

In these views the reference numeral 5 55 indicates the face of the body portion which may be of any desirable material, and contour, and to the rear of which a suitable liner 6 may be provided.

The object of the mask may also conveniently include indentations 7 adjacent its side edges affording a reinforcing medium, and is also formed with sight openings 8, and a nose portion 9.

Contrary to the conventional construction, 65 however, in which the face terminates in line with the lower edge of the body portion, i. e., the lower edge of the liner, the face portion is extended to form an apron 10, extending below the lower edge of the 70 body of the mask, as has been clearly indicated.

By this construction, it will be seen that the liner 6, if the same is used, may be applied in the usual manner to the rear of the 75 face portion 5 of the mask subsequent to which a single die may be utilized, to not alone press the line into intimate engagement with the face, forming the indentations 7, sight openings 8, etc., but will also 80 provide the apron 10.

Thus a second cutting operation is eliminated, aside from the fact that it is no longer necessary to attach the apron 10 to the body 85 of the mask.

Obviously numerous modifications of structure might readily be resorted to without in the least departing from the spirit of my invention, which I claim as:—

As an article of manufacture, a mask including a body portion adapted to overlie the eyes and nose of a wearer, a sheet of material forming a part of said body portion, and a liner affixed to the rear face of said material, said material being extended 90 beyond the lower edge of said liner and the body portion, whereby to provide an integral apron. 95

FRANKLIN MASON DESSART.
